WALTER R. CLARK, OF BRIDGEPORT, CONNECTICUT, ASSIGNOR TO BRIDGEPORT BRASS COMPANY, OF BRIDGEPORT, CONNECTICUT, A CORPORATION OF CONNECTICUT.

COILING APPARATUS.

1,291,669.

Specification of Letters Patent. Patented Jan. 14, 1919.

Application filed February 28, 1917. Serial No. 151,565.

To all whom it may concern:

Be it known that I, WALTER R. CLARK, a citizen of the United States, residing in Bridgeport, in the county of Fairfield and 5 State of Connecticut, have invented certain new and useful Improvements in Coiling Apparatus, of which the following is a full, clear, and exact description.

This invention relates to metal coiling apparatus, and it refers more particularly to 10 certain improvements in the apparatus disclosed in my Patent No. 1,258,092, granted March 5th, 1918.

In this patent there is disclosed a blocker, 15 comprising a coiling device adapted to give the strip a coiling bend or set as it issues from the rolling mill or other machine, in combination with a block located in the line of feed of the forward end of the bent 20 strip, so that the coiling device will lay the strip on the block. The radius of the curve imparted to the strip by the coiling rolls or the like is properly chosen with regard to the radius of the block, so that as the strip 25 is fed forward around the block it will hug the same closely, until one layer has been laid on the block, after which the forward extremity of the strip is clamped by the beginning of the second layer or convolution, 30 the block being driven at a higher rate of speed than the normal feed of the strip, so as to tension the strip and cause it to wind tightly on the block in a plurality of overlapping convolutions of successively increasing 35 diameter. Another feature of my prior machine is the provision made for forming an open coil by means of the coiler, for which purpose the coiling rolls and block are relatively movable, preferably by having 40 the block mounted to swing toward and away from the coiling roll. It will therefore be seen that in my prior device when the block is located over the coiling rolls, the same will coöperate with these rolls in 45 blocking, and when moved away from the coiling rolls, the latter may be used independently in forming an open coil, the block being idle during this operation.

One of the primary objects of the present 50 invention is to provide a machine or apparatus of the general character above stated, but differing therefrom as hereinafter pointed out, which is very compact, efficient and easily operable.

55 Another object of the invention is to pro-

vide a coiling apparatus in which the block and the coiling rolls are mounted on the same frame, and wherein the operation of the apparatus may be very readily controlled.

60

A further object which I have in view is the provision of an apparatus in which the swingingly mounted blocker has a comparatively small movement toward and away from the coiling rolls, and in which provision is made for rotating the block in a reverse direction, after the winding operation is completed, for the purpose of unwinding the coil to a slight extent, so that it can be readily removed from the block.

65

Another object of the invention is to provide an apparatus of the character stated, in which the coiler, coöperating with the block, is automatically controlled as the block is moved toward and away from the 75 position in which it receives the strip from the mill, said coiler being automatically moved into a position to grip the strip when the block is moved into strip-receiving position, and being automatically caused to disengage the strip when the block is moved away from the mill to its winding position. By opening the coiling rolls or their equivalents when the block is moved to one position, said rolls will no longer crimp or set 80 the strip, and the movement of the rolls into and out of the crimping position is effected automatically without requiring attention on the part of the operator.

85

A still further object of the invention is 90 to improve the general construction and operation of apparatus of the class indicated.

To these and other ends, the invention consists in the novel features and combination of parts to be hereinafter described and 95 claimed.

In the accompanying drawings,

Figure 1 is a side elevation of one form 100 of coiling apparatus embodying my improvements, looking toward that side of the machine or apparatus which is located away from the mill, certain parts being broken away;

Fig. 2 is a section of the machine on line 2-2 of Fig. 1, looking from the right hand 105 end of the machine, showing the block in position to receive the strip at the commencement of the blocking operation;

Fig. 3 is another transverse section of the machine, showing the block in the winding 110

position, after blocking operation has been started;

Fig. 4. is a sectional elevation, looking from the left hand end of Fig. 1, showing the block in the initial position corresponding to Fig. 2;

Fig. 4^a is a detail of certain parts shown in Fig. 4;

Fig. 5 is a view generally similar to Fig. 4, showing the block in the winding position corresponding to Fig. 3;

Fig. 6 is a section on line 6—6 of Fig. 1;

Fig. 7 is an enlarged fragmentary view of the coiler, looking from the left hand end 15 of Fig. 1, showing the coiling rolls separated;

Fig. 8 is a section of the parts shown in Fig. 7, with the coiling rolls in position to crimp or bend the strip;

Fig. 9 is an enlarged fragmentary view 20 of the coiling rolls;

Fig. 10 is a fragmentary top plan view of certain parts shown in Fig. 7;

Fig. 11 is a detail section on line 11—11 of 25 Fig. 10;

Fig. 11^a is a detail of the supporting means for the lower coiling rolls;

Fig. 12 is a fragmentary sectional view 30 of the clutch mechanism for driving the block, showing it in the normal position;

Fig. 12^a is a detail of certain parts shown in Fig. 12; and

Fig. 13 is a view similar to Fig. 12, showing the clutch in a position to reverse the 35 direction of drive of the block.

Referring to the drawings, and more particularly to Fig. 2, the rolls of the mill or other machine from which the strip issues are shown diagrammatically at 20, and associated with these rolls are guides 21 of 40 well known type which direct the strip to the coiling apparatus. This coiling apparatus comprises a frame or table 22, with which are associated a rotary block 23 and 45 a coiling device 24.

In order that the coiling apparatus may be conveniently moved into and out of cooperation with the rolling mill as required, the table 22 is mounted on a guide frame 50 25, on which it is slidable in a direction parallel to the axes of the mill rolls. In this manner, the apparatus may be pushed or pulled into and out of the path of the strip emerging from the rolls, and when the 55 table 22 reaches the desired position longitudinally of the guide frame 25, it may be clamped in position by suitable means, such as, for example, a lock or brake 26 operated by a hand wheel 27 mounted on the lower 60 part of the table. Referring now more particularly to Fig. 1, it will be observed that the block 23 and coiling device 24 are located on top of the table or frame 22 and toward one end of the same. The coiling device 65 comprises a plurality of coiling rolls mount-

ed in side frames or standards 28, 28^a set on the table 22. At the opposite end of the table, a bracket 29 is provided and a driving shaft 30 is journaled at one end in this bracket and at the opposite end in the side frame 28^a. This driving shaft 30 may be driven by a belt engaging a pulley 31 on said shaft, or in any other suitable manner. The block 23 which preferably consists of the inner structure 23' and the outer shell 23^a is fixed to a rotating block shaft 32 extending horizontally lengthwise of the table parallel to the main driving shaft 30 and having a portion overhanging and parallel to the set of coiling rolls 24. This block 70 shaft 32 is adapted to be swung into the position shown in Fig. 2, so that the strip will be coiled about the block for commencing the blocking operation, and after the strip has been laid on the block, the latter is swung away from the mill into the position shown in Fig. 3 to obtain a straight pull of the strip from the mill, at which time the coiling rolls 24 are disengaged 75 from the strip so that they no longer crimp or bend the same. In order to produce the necessary movement of the blocker shaft 32, the same is, in this instance, mounted to swing about the axis of the main shaft, and suitable mechanism is provided for producing the necessary swinging movement to 80 shift the block from receiving to winding position, and vice versa. In the form shown, the block shaft 32 is mounted in a carrier member 33 to rotate therein, and the carrier member is in turn mounted on the driving shaft to swing freely thereon. The carrier 33 is preferably of hollow form, like a casing, to inclose certain gears on the main shaft, and it is provided with sleeve 85 portions 33^a, 33^b fitting over the shaft 30 and constituting bearings on which the carrier may swing relatively to the shaft. An extension 34 on the sleeve 33^a carries at its upper end a split bearing 35 for one end of 90 the block shaft 32. At the opposite side of the hollow frame or carrier 33, an extension 36 extending upward from the sleeve 33^b has a split bearing 37 for the intermediate portion of the block shaft. It will be 95 understood, therefore, that by providing this mounting, the carrier and the block shaft carried thereby may be swung from the position shown in Fig. 2 to that shown in Fig. 3, and vice versa, with the shaft 30 100 serving as the pivotal point of support.

During most of the operation the block or drum 23 is driven from the main shaft 30 by means of a pinion 38 fixed to said shaft within the carrier casing, and engaging a gear 39 on the block shaft 32. This gear 39 is mounted loosely on the shaft, but it may be locked thereto by means of a sliding clutch member 40 splined to the shaft 32, as hereinafter described. The pinion 38, 105

gear 39, and clutch member 40 are all located in the carrier casing. The carrier has at the bottom a wall 41 connecting the bearing sleeves 33^a, 33^b, and at the top the casing is completed by another casing member 42 which may advantageously consist of a light sheet metal shell suitably connected with the frame work.

The block is swung to and fro in the present instance by fluid pressure mechanism acting on the swinging frame or carrier 33. At that side of the carrier which is located toward the block, the same has applied thereto a gear segment 43, as shown more particularly in Fig. 4, said segment being concentric with the main shaft. An upwardly extending rack 44 engages this gear segment, and is held in contact therewith by a roller 45 journaled on a pin 46, mounted on a bracket 47, which in turn is mounted on the top 22^a of the table 22. The rack 44 is carried at the upper end of a piston rod 48, of a piston (not shown) working in a substantially upright fluid pressure cylinder 49. This cylinder is adapted to be supplied with motive fluid from any suitable source (not shown), and the direction of movement of the piston is controlled by the actuation of any suitable or preferred form of controlling valve 50, which it is not necessary to describe in detail. A horizontal rock shaft 51 journaled in the lower part of the table serves as a support for the lower end of the cylinder 49, the latter being provided with 35 perforated ears 52 loosely fitting over said shaft, so that the latter may turn freely while still supporting the cylinder from beneath in an efficient manner. The movement of the rock shaft 51 is utilized for actuating the valve 50, for which purpose an arm 53 fixed to the shaft is suitably connected with the valve by means of a link 54. The shaft is provided at the end with a treadle 55, by means of which it may be conveniently 45 rocked to actuate the valve 50. A spring 56 connected at one end with the treadle 55, and at the other end with the frame of the machine normally holds the treadle 55 in the position shown in Fig. 4. In this position, 50 the piston rod 48 occupies its lowermost position, and the rack 44 and gear segment 43 are in such a position that the block is located over the coiling device 24 so as to receive the strip therefrom. When, however, 55 the treadle 55 is depressed, in opposition to the spring 56, compressed air will be admitted to the cylinder 49 by the valve 50, so as to raise the piston and piston rod, and thereby the rack 44 is raised to the position shown 60 in Fig. 5, and it turns the gear segment 43 to such an extent as to swing the carrier 33 on the main shaft until the block assumes a winding position in which its lower surface is approximately in horizontal alinement 65 with the bite of the mill rolls. In this way,

a straight pull from the mill is obtained after the strip has been caught on the block. When the treadle 55 is fully depressed to actuate the piston, a pivoted latch 57 on the frame, controlled by a spring 58, automatically engages at one end in a notch 59 in the treadle 55 to lock said treadle in the fully depressed position, so that the block will continue to be held in the winding position shown in Fig. 5 when the foot of the operator is removed from the treadle. In other words, the construction is such that it is not necessary for the operator to hold the treadle down throughout the operation of winding; it can be released as soon as the block has 70 been moved to winding position. When, however, the winding operation is completed, and it is desired to move the block back to the receiving position, shown in Fig. 4, to receive another strip, the operator places his 75 foot on a small treadle piece 60, carried by the spring latch 57, and thereby causes the latch to disengage the treadle 55, which thereupon rises under the influence of the spring 56, actuating the valve 50 to exhaust 80 the cylinder 49, and thereby causing the rack 44 to descend and swing the block back to the coil-receiving position. When the block is again moved to the winding position, the spring latch 57 will again snap into locking 85 engagement with the notch 59 in the treadle 55 under the influence of the spring 58.

The general arrangement of the coiling rolls 24 is quite similar to that described in my Patent No. 1,258,092 above mentioned. 100 As shown more particularly in Fig. 8, a three-roll coiler is employed in the present machine, involving an upper coiling roll 61 and two lower coiling rolls 62, 63 cooperating therewith. The strip from the mill is 105 fed between the roll 61, on the one hand, and the two rolls 62, 63, on the other hand, and is thus given a bend or set tending to coil it about the block 23 when the latter is positioned over the coiling rolls. When it 110 is desired to use the device described in this application to form an open coil, the operation of the device is necessarily somewhat different from the operation of the machine disclosed in my patent above mentioned. In 115 the latter machine, when it is desired to wind an open coil, the block is swung away from over the coiling rolls, in order that the open coil may be formed above the coiling rolls independently of the block, but the device described in this application will not operate in this manner since, due to the mechanism hereinafter described by which the coiling rolls 62 and 63 are automatically moved away from the roll 61 when the block 120 23 is swung away from the position above the coiling rolls, no coiling function is performed by the coiling rolls when the block is swung to the position shown in Fig. 3, since the coiling rolls are always separated 125 130

when the block is in this position, as will be seen upon a careful inspection of the rolls in this figure. It is therefore necessary that the carrier 33, in which the shaft 32 is rotatably mounted, should remain in the position shown in Fig. 2 throughout the operation of forming open coils, in order that the coiling rolls 61, 62 and 63 will remain in crimping engagement with the strip being coiled. This operation is made possible by simply removing the block 23 from its shaft 32, so that the open coils will be formed in a relatively large roll about the shaft 32 but out of contact with the same, since the diameter of the shaft is much smaller than the inner diameter of the coil formed about the same. When an open coil is to be formed about the shaft 32 after the block 23 has been removed from the same, the strip, after passing through the coiling rolls, forms an open coil above these rolls, and this coil will rest on supporting rolls 64 and will be held in the proper position by a guard member 65. The upper coiling roll 61 has fixed bearings in the side frames 28, 28^a, but the lower rolls 62, 63 are vertically movable to engage or disengage the strip, as hereinafter explained.

The gears for driving the coiling rolls are shown more particularly in Figs. 6 and 8. These rolls are driven from the main shaft 30 which carries a gear 66 adjacent the right hand side of the coiling rolls (Fig. 1). This gear 66 engages a gear 67 on the shaft 61^a of the upper coiling roll 61. The shaft 61^a also carries adjacent the gear 67 a second gear 68 which drives the supporting rolls 64 in the proper direction by engaging gears 69 on the shafts of said rolls. The lower rolls 62, 63 are driven from the gear 69, which drives through idle gears 70, 71, a gear 72 fixed to a longitudinal shaft 73 located immediately beneath the rolls 62, 63, thereby rotating said shaft. At the left hand side of the machine (Fig. 1) the shaft 73 carries a gear 74, engaging gears 75, 76 respectively on the shafts of the lower coiling rolls 62, 63 respectively, whereby said coiling rolls are rotated in a proper direction.

The coiling rolls 62, 63 and the shaft 73 are journaled in bearing members 77, one at each side of the coiler frame, and these bearing members or blocks 77 are guided in the frames 28, 28^a for vertical movement, for which purpose said frames are cut away to form suitable vertical guides 78, as shown more particularly in Figs. 7 and 8. Beneath the bearing blocks 77, a supporting block 79 extends longitudinally of the coiler from one side frame to the other, the end portions of said supporting block being located beneath and supporting the respective bearing blocks. By raising the block 79, the rolls 62, 63 may therefore be raised in the

guide 78 so as to crimp the strip, as shown in Fig. 8, and by lowering the block 79, the rolls 62, 63 will be permitted to descend to a position in which they disengage the strip, as shown in Fig. 7. In order to produce the automatic raising and lowering movement of these lower coiling rolls, I provide suitable mechanism which, in the present instance, is actuated from the main shaft 30 at the proper time. In the example shown, the carrier or frame 33 is provided at the left hand side (Fig. 1) with a cam 80, adapted to engage a roller 81 on a crank 82 (Fig. 8) fixed to one end of a shaft 83 journaled in the side frames 28, 28^a of the coiler at the lower part thereof, whereby when the carrier 33 is swung to move the block, the shaft 83 will be rocked. This shaft 83 is provided at different points with toggle connections with the bearing-supporting blocks 79 previously mentioned. Each toggle consists of a link 84 connected with the rock shaft 83 and pivoted to another link 85, which in turn is pivoted at 86 to ears 87 depending from the lower surface of the supporting block 79, as shown in Fig. 8. When the cam 80 is in the position shown in Fig. 8, the toggle connections are straightened so as to raise the bearing blocks 77 by means of the supporting block 79, in order that the lower coiling rolls will then coat with the upper coiling roll 61 to bend or set the strip; but when the cam 80 is moved to the position indicated in Fig. 7, the toggle joints are "broken", and the coiling rolls are permitted to descend by their weight into an inoperative position, in which they do not engage the strip. The cam 80 is so constructed and arranged relatively to the block carrier that when the block is in the receiving position shown in Fig. 8, the coiling rolls will be in a position to catch and crimp the strip, but when the block is moved to the winding position, after the coil has been started, the rolls will be automatically disengaged from the strip.

In order to provide for a fine adjustment of the lower coiling rolls 62, 63 relatively to the upper coiling roll 61, I prefer to furnish means for adjusting the bearings 77 with respect to the supporting block 79. In the particular example illustrated, vertical threaded spindles 88, engaging threaded sockets in the block 79, adjacent the respective ends of the coiler frame, are adapted to impinge at their upper ends against the lower surfaces of the respective bearing members 77, and as the spindles 88 are turned in one or the other direction, the bearings of the rolls will be raised or lowered. The necessary turning movement can be imparted to the spindles 88 by means of worm gears 89 on the lower ends thereof engaging worms on a horizontal shaft 90, having bearings at its ends in the supporting

block 79 and provided at one end with an operating hand wheel 91, as shown in Fig. 7. It will therefore be understood that by turning the hand wheel 91 in one direction, 5 the spindles 88 can be screwed up in their threaded sockets to engage and raise the bearings 77, so that the rolls 62, 63 can be caused to give the strip exactly the desired bend or set. If when the rolls are in the 10 operative position it is found that they are putting too much of a crimp in the strip, the lower rolls will descend by gravity if the hand wheel 91 is turned in the opposite direction to draw down the upper ends of 15 the threaded spindles 88. Intermediate of the ends of the shaft 90 the same has associated therewith a gage device, whereby the position of the lower coiling rolls may be indicated, and by which the proper adjustment 20 of the rolls is considerably facilitated. This gage device comprises a traveling pointer member 92 having threaded engagement with a portion of the shaft 90 and movable over a scale 93. By ascertaining 25 the position of the pointer relatively to the scale, the space between the lower coiling rolls, on the one hand, and the upper coiling roll, on the other hand, can be quickly and readily determined, and if the bite of 30 these rolls is not suitable for the thickness of the strip to be coiled, the necessary adjustment can be quickly made by turning the hand wheel 91 in the proper direction.

The adjustment of the coiling rolls by 35 means of the cam 80 does not interfere in any way with the gage device, as the latter is entirely supported on the movable supporting member 79. The gear drive of the lower coiling rolls is also not interfered 40 with in any way by the vertical movement imparted to said rolls, as the gear 72 is not shifted sufficiently to disengage the gear 71. When the coil has been completely wound on the block, it is usually desired to slide it 45 off the block endwise, and this cannot be done readily unless the block is collapsed in some manner or the coil is slightly unwound. In the present machine, I provide for the unwinding of the coil to a slight extent at the completion of the blocking operation, so that the coil can be readily taken 50 off the block, and this is achieved by momentarily reversing the direction of rotation of the block. This result can be very 55 readily achieved by actuating the reversing mechanism shown in detail in Figs. 12, 12^a and 13. When the parts are in the position shown in Fig. 12, the clutch member 40 previously mentioned, which is splined to 60 the block shaft 32, engages the gear 39 to lock it to the block shaft, so that the pinion 38 (Fig. 1) will be effective to rotate the block in the normal direction for blocking. When, however, it is desired to reverse the 65 block, the clutch member 40 is actuated to

engage a gear 94 freely rotatable on the block shaft within the casing of the carrier 33. This gear 94 is driven oppositely to the gear 39 because it is actuated from the shaft 30 through an intermediate pinion 95 best 70 shown in Fig. 2, which intermediate pinion is driven by a gear 96 on the main shaft. In other words, by interposing the pinion 95 between the gears on drive shaft and block shaft respectively, instead of causing the 75 gears to directly engage (as is the case with the gears 39, 38), the direction of drive of the block shaft is reversed, when the clutch member 40 is actuated to couple the gear 94, 80 to the block shaft. In the particular form 85 shown, the clutch member 40 has teeth 41^a to engage a toothed engaging member 41^b on gear 39, and said clutch member has a flat friction surface 94^a to engage a co-operating friction surface on the gear 94, 90 but these details are not essential. The clutch member may be shifted in the usual manner by a fork 97, pivoted inside the casing at 98, and extending through a slot in the casing 33. This forked lever 97 is 95 adapted to be operated by a slide rod 99, having a yoke 100, in which the end of the lever is engaged, and the slide rod 99 is actuated from a treadle 101, mounted to swing on the shaft 51, and connected by a rod 100 102 to the slide rod 99 through an elbow lever 103, pivoted on the frame at 104. A spring 105 acting on the slide rod 99 normally holds the clutch in a position to drive the block in the winding direction, but by depressing the treadle 101, as shown in Fig. 13, the slide rod may be slid to move in opposition to the spring 105, so as to actuate the lever 97 to reverse the clutch. The treadle 101 is only depressed momentarily so as to 105 unwind the coil only to such an extent as to permit the same to be readily moved off the free end of the block.

My machine may be used either as a blocker or as an open coiler, and it is very 110 efficient in performing both of these operations. The machine is very compact in construction, and the controls are simple and few. Only one attendant is required, and as the machine is very rapid in operation, the 115 output during a given interval of time is very large. The machine can be very easily handled without fatigue on the part of the attendant, and it may be adjusted to meet a large number of varying conditions, in 120 spite of its comparatively simple mechanism. I have not attempted to illustrate or describe the various modifications of the construction which may be adopted without departing from the scope of the invention. 125 I do not limit myself to a machine in which the coiling device is constituted by three coiling rolls, nor do I limit myself to a construction wherein the coiler is opened and closed by movement of two lower coiling 130

rolls, nor to a construction in which one or more coils are adapted to be raised and lowered by connections with the block carrier. Furthermore, I do not limit myself to a machine in which the various controls are effected by the actuation of treadles, as distinguished from other controlling members. Various changes in these and other details may be made without departing from the 10 scope of the invention as defined in the claims.

It will be observed that by mounting the block shaft to swing relatively to the axis of the drive shaft, and rotating said block 15 shaft by a gear thereon meshing with a gear on the drive shaft, the block can be rotated regardless of its swinging movement to and from coil-receiving position, as the gears are always in mesh. Furthermore, 20 the construction of the machine is made simple and compact by mounting the coiling rolls and the block on the same table, and by driving them from a common drive shaft located on the same table, preferably by 25 gearing as shown.

What I claim is:

1. The combination of a coiling device, a block movable into and out of coöperation therewith, said coiling device adapted 30 to be closed on the strip to bend or crimp the same and to be opened so as to disengage the strip, and means operated automatically by the movement of the block for controlling the condition of said coiling device.

2. The combination of a coiling device, a block movable into blocking coöperation therewith, said coiling device composed of parts movable into and out of operative 40 position, and means for moving said parts to operative position automatically as the block is moved to the blocking position.

3. In coiling apparatus, the combination of a coiler composed of parts movable to engage or disengage the strip, a block, and means for simultaneously moving the block 45 into blocking coöperation with the coiler and engaging the coiler with the strip.

4. In coiling apparatus, the combination of a coiler composed of parts adapted for adjustment to crimp the strip or to disengage the same, a block, and means for moving 50 said block into coöperation with said coiler and for adjusting said coiler to crimp the strip.

5. In coiling apparatus, the combination of coiling rolls adapted for adjustment to bend the strip or to disengage the same, a block, and means for simultaneously moving 55 the block into blocking coöperation with the coiler and setting the coiling rolls to bend the strip around the block.

6. In coiling apparatus, the combination of a coiler composed of parts adapted to 65 gage the strip to bend the same, a block

on which the coiler lays the strip in successive convolutions, means for moving the block away from the coiler, and means controlled by said last-named means to disengage the coiler from the strip.

7. In coiling apparatus, the combination of a coiler, a block, means for moving the block into coöperation with the coiler, and means controlled by said last-named means for adjusting the coiler to engage and bend 75 the strip around the block.

8. In coiling apparatus, the combination of coiling rolls having a bite for crimping the strip, a block to receive the strip, means for moving said block into and out of operative position with respect to said coiling rolls, and means controlled by said last-named means for moving said coiling rolls automatically into strip bending position 80 when the block is moved to operative position.

9. In coiling apparatus, the combination of a coiling device composed of coiling rolls adjustable to engage and bend the strip between the same and to disengage the strip 85 when said rolls are separated, a block mounted to swing into and out of coöperation with said rolls, power actuated means for swinging said block, and means controlled by said power actuated means for 90 adjusting the coiling rolls to operative position automatically when the block is moved into operative position and for disengaging said coiling rolls from the strip automatically when the block is swung away from 95 said rolls.

10. The combination with a rolling mill, of a table located on the discharge side of the mill, said table movable into and out of the path of the emerging strip, and a combined open coiler and blocker mounted on 105 said table, said coiler being positioned to coil the strip upon said blocker.

11. In coiling apparatus, the combination of a table or frame, coiling rolls carried 110 thereby, a block on said table or frame, a driving shaft on said table or frame, and means geared to said shaft for simultaneously driving said coiling rolls and said block.

12. In coiling apparatus, the combination of a table or frame, coiling rolls mounted thereon, a drive shaft for said coiling rolls, and a block mounted to swing on the axis of 115 said drive shaft.

13. In coiling apparatus, the combination of a table, a set of coiling rolls mounted thereon, a block above said coiling rolls, and a swinging carrier member for said block mounted on said table, alongside said 120 coiling rolls, whereby said coiling rolls and block are carried by said table.

14. The combination of a table, a set of coiling rolls mounted thereon, a drive shaft for said coiling rolls, a swinging carrier 125

member mounted on said table, a block carried by said member and movable into and out of coöperation with said rolls, whereby said coiling rolls and block are carried by 5 said table, and power actuated means for swinging said block relatively to said rolls.

15. The combination of a table, a set of coiling rolls mounted thereon, a drive shaft for said rolls, a swinging carrier mounted 10 to turn on the axis of said drive shaft, a block on said carrier to coöperate with said rolls, and means mounted on the table for actuating the carrier and block.

16. The combination of a table or frame, 15 a set of coiling rolls mounted thereon, said rolls adjustable toward and away from each other, a drive shaft for said rolls mounted on said table or frame, a swinging carrier mounted on said table or frame, a block carried thereby and movable into and out of coöperation with said coiling rolls, and automatic adjusting mechanism for said coiling rolls controlled by the shifting of said block.

25. 17. In coiling apparatus, the combination of a table, a coiler mounted thereon, means on the table to drive the coiler, a block mounted on the table, means for driving the block, power actuated means for moving the 30 block into and out of coöperation with the coiler, and power actuated means for adjusting the coiling action of the coiler on the strip.

18. In coiling apparatus, the combination 35 of a table, a coiler mounted thereon, means on the table to drive the coiler, a block mounted on the table, means for driving the block, power actuated means for moving the block into and out of coöperation with the 40 coiler, and power actuated means for adjusting the coiling action of the coiler on the strip, said adjusting means operated automatically by said block moving means.

19. In coiling apparatus, the combination 45 of a table, coiling rolls mounted thereon, means for driving said rolls, a block on the table, means for moving said block into and out of coöperation with said coiling rolls, and means for driving the block in one direction to coil the material thereupon and in the opposite direction to loosen the coils about the block.

20. In coiling apparatus, the combination 50 of a frame, a drum or block mounted thereon, means to rotate the same, means on said frame to curve the strip around the block, and means to reverse the rotation of the block to loosen the inner coils of the strip about the block.

60. 21. In coiling apparatus, the combination of a frame, a coiler thereon adapted to give the strip a curve or bend of definite radius, a rotary block to coöperate with said coiler, a drive shaft, and means interposed between 65 said drive shaft and said block for driving

the block in one direction to coil the material thereupon and in the opposite direction to loosen the coils about the block.

22. In coiling apparatus, the combination 70 of a coiler, a drive shaft therefor, a block positioned to receive material delivered thereto by said coiler, a block shaft, and clutch mechanism interposed between said drive shaft and said block shaft.

23. In coiling apparatus, the combination 75 of a coiler, a drive shaft therefor mounted on the table, a block located over the coiler, a block shaft, means for shifting the block shaft to carry the block into and out of coöperation with the coiler, and means interposed between the block shaft and drive shaft for rotating the block in either direction.

24. In coiling apparatus, the combination 80 of coiling rolls, a block shaft, a block carried thereby, means to shift the block shaft to move the block into and out of coöperation with said coiler, a drive shaft operatively connected with the block shaft, and clutch mechanism for driving the block in one or 85 the other direction.

25. The combination of a rolling mill, a three-roll coiler to engage the strip emerging from the mill, a block adapted to receive the strip from the coiler, and a framework 95 on which said coiler and block are mounted, said framework movable transversely with respect to the path of the strip.

26. In metal coiling apparatus, the combination 100 of a frame, coiling rolls mounted thereon, a drive shaft on said frame for rotating said rolls, a drum or block, a shaft for said drum or block, a carrier for said last-named shaft mounted to swing on the axis of said drive shaft, and means actuated 105 from the drive shaft for rotating the block shaft.

27. In metal coiling apparatus, the combination 110 of a frame, coiling rolls mounted thereon, a drive shaft on said frame for rotating said rolls, a drum or block, a shaft for said drum or block, a carrier for said last-named shaft mounted to swing on the axis of said drive shaft, and means actuated from the drive shaft for rotating the block 115 shaft in either direction.

28. In coiling apparatus, the combination 120 of a frame, coiling rolls mounted thereon, said rolls adjustable toward and away from each other to engage and disengage the strip, a drive shaft for said rolls, a block to coöperate with said rolls, a carrier for said block, means for rotating said block, and means controlled by the position of said carrier for adjusting the bite of said coiling 125 rolls.

29. In coiling apparatus, the combination 130 of a frame, coiling rolls mounted thereon, a drive shaft for said coiling rolls mounted on said frame, a carrier mounted to swing

- on the axis of said drive shaft, a block shaft mounted on said carrier, a block on said shaft to coöperate with said rolls, mechanism mounted in the frame for swinging the carrier to move the block into and out of coöperation with said rolls, and mechanism controlled by the position of said carrier for adjusting the bite of said coiling rolls.
- 10 30. The combination with a rolling mill or the like, of a coiler, a drum or block to coöperate with the coiler in blocking the material issuing from said mill, said drum or block mounted to swing away from the coiler to obtain a straight pull from the mill, and means actuated automatically when said drum or block is so swung for disengaging the coiler from the strip.
- 20 31. In coiling apparatus, the combination of a coiler, a block movable into and out of coöperation with the coiler, means normally holding said block in coöperation with said coiler to receive the strip emerging from the latter, and a treadle-controlled means to move the block away from the coiler into position for winding.
- 30 32. In coiling apparatus, the combination of a coiler, a swingingly-mounted rotary block movable to a coil receiving position over the coiler or to a winding position away from the coiler, valve operated means for moving said block from one position to the other, and means for operating said valve, comprising a lever normally retained in one position and a member for automatically locking said lever out of its normal position when the latter is moved therefrom.
- 40 33. In coiling apparatus, the combination of a coiler, a swingingly-mounted block having a coil receiving position over the coiler, and a winding position away from the coiler, means normally holding the block in coil receiving position, power actuated means for shifting said block into the winding position, means for driving the block, and means for reversing the rotation of the block when the winding operation is completed, for loosening the coil.
- 50 34. In coiling apparatus, the combination of coiling rolls adjustable toward and away from each other, a block to coöperate with said rolls, power actuated mechanism for moving said rolls into and out of operating position, and manually operated means for adjusting said rolls relatively to said power operated mechanism.
- 60 35. In coiling apparatus, the combination of a table, coiling rolls mounted thereon, a drive shaft for said coiling rolls mounted on said table, gearing connecting said drive shaft with said rolls, a block shaft mounted on said table, gearing connecting said block shaft with said drive shaft and a block upon said block shaft positioned to have a strip coiled about the same by said coiling rolls.
36. In coiling apparatus, the combination of a coiling device, a block, a block shaft, a drive shaft for the coiler, said block shaft mounted to swing relatively to the axis of said drive shaft, a gear on the drive shaft, and a gear on the block shaft meshing therewith, irrespective of the swinging movement of the block shaft.
- 70 37. In coiling apparatus, a supporting frame, a table adjustable relatively to said frame, a coiler mounted on said table, a block mounted on said table to coöperate with said coiler, whereby said coiler and block are carried by said table and adjustable therewith, and a common drive shaft for the coiler and block.
- 75 38. In coiling apparatus, the combination of a frame, a coiler mounted thereon, a block to coöperate with said coiler, a drive shaft for said coiler mounted on said frame, means for mounting said block for swinging movement about said drive shaft, and means for driving said block from said drive shaft.
- 80 39. In coiling apparatus, the combination of a frame, a coiler mounted thereon, a block to coöperate with said coiler, a drive shaft for said coiler mounted on said frame, means for mounting said block for swinging movement relatively to said drive shaft, and means for driving said block from said drive shaft, irrespective of the swinging movement of the block, comprising permanently intermeshing gears on the drive shaft and block shaft respectively.
- 90 40. In apparatus such as described, the combination of a drive shaft, a carrier mounted to swing on the axis of said shaft, a block shaft mounted on said carrier and reversible transmission mechanism interposed between the drive shaft and the block shaft for driving the latter in either direction.
- 100 41. In apparatus such as described, the combination of an adjustable table, a coiler on said table, a swingingly-mounted block on said table movable into position to receive the material operated upon by said coiler, and a common drive shaft for the coiler and block also mounted on said table, whereby said coiler and block are adjustable with said table.
- 110 42. The combination with a rolling mill or the like, of a coiler, a drum or block mounted to be swung into position to have the material tightly laid on said drum by said coiler and to be swung to a second position to obtain a straight pull from the mill, and means actuated automatically as said drum is swung to said second position to disengage the coiler from the material passing therethrough.
- 120 43. The combination with a rolling mill or the like, of a coiler, a drum or block mounted to be swung into position to receive the material acted upon by said coiler and to be swung to a second position to obtain a

straight pull from the mill, and means actuated automatically when said drum is swung to said second position to disengage the coiler from the material passing therethrough.

5 44. The combination with a rolling mill or the like, of a coiler, a drum or block mounted to be moved into one position relatively to said coiler to receive the first few coils of material wound upon said drum, and to a second position relative to said coiler to complete the winding of the material upon said drum, and means actuated automatically when said drum is moved to said second position to disengage the coiler from the material passing therethrough.

10 45. In coiling apparatus, a supporting frame, a table adjustably mounted on said frame, a coiler upon said table, a block co-operating with said coiler swingingly mounted upon said table, whereby said coiler and block are adjustable with said table, and power-operated means mounted upon said table for moving said block relatively to said coiler.

25 46. In coiling apparatus, the combination of a table, a drum or block mounted thereon, means to rotate the drum or block to wind the strip around the same, and means to reverse the rotation of said block to loosen the inner coils of the strip about the block.

30 47. In a coiling apparatus, a drum or block, means to rotate the drum or block to wind the strip around the same, and means to reverse the rotation of said drum or block to loosen the inner coils of the strip about the block, whereby the coiled strip may be readily removed from the block.

35 48. In coiling apparatus, the combination

of a coiler composed of parts movable to engage or disengage the strip, a block bodily movable relatively to said coiler, a swinging carrier supporting said block, a cam upon said carrier, and means operated by said cam when said carrier is shifted for engaging the coiler with the strip.

40 49. In coiling apparatus, the combination of coiling rolls adjustable toward and away from each other, a block mounted to be moved into and out of coöperation with said rolls, means whereby the movement of said block relatively to said rolls automatically adjusts said rolls relatively to each other, and manually operated means for adjusting said rolls independently of said automatic adjustment thereof.

45 50. In coiling apparatus, the combination of coiling rolls adjustable toward and away from each other, a block, a movable carrier for supporting said block, means operated by the movement of said carrier for automatically adjusting said rolls, and manually operated means for adjusting said rolls independently of said automatic adjustment thereof.

55 51. The combination with a rolling mill, of a table adjustable relatively to said mill, a coiler upon said table, and a block coöperating with said coiler swingingly mounted upon said table, said table, coiler and block movable as a unitary structure into and out of the path of the strip emerging from said mill.

In witness whereof, I have hereunto set my hand on the 27 day of February, 1917.

WALTER R. CLARK.
